Primary Examiner — Eric Goodman*Assistant Examiner* — John Reickel(74) *Attorney, Agent, or Firm* — Milton's IP/p.i.(57) **CLAIM**

The ornamental design for a solarium equipment, as shown and described.

DESCRIPTION

FIG. 1 is a top left perspective view of the design as applied to solarium equipment in an open position.

FIG. 2 is a front offset perspective view of the design of FIG. 1 in an open position.

FIG. 3 is a top right perspective view of the design of FIG. 1 in an open position.

FIG. 4 is a front view of the design of FIG. 1 in an open position.

FIG. 5 is a top view of the design of FIG. 1 in an open position.

FIG. 6 is a bottom front left perspective view of the design of FIG. 1 in an open position.

FIG. 7 is a bottom back left perspective view of the design of FIG. 1 in an open position.

FIG. 8 is a bottom front right perspective view of the design of FIG. 1 in an open position.

FIG. 9 is a bottom back right view of the design of FIG. 1 in an open position.

FIG. 10 is a cross-section right view of the design of FIG. 12; FIG. 11 is a cross-section left view of the design of FIG. 12; and,

FIG. 12 is a view of the design of FIG. 1 offset at an angle and in a closed position.

The broken line(s) which define the bounds of the claimed design form no part thereof.
